UNITED STATES PATENT OFFICE.

LOWELL C. MASON, OF PROVIDENCE, RHODE ISLAND, ASSIGNOR TO THE
SETH W. BAKER MANUFACTURING COMPANY, OF SAME PLACE.

TEMPLE FOR LOOMS FOR WEAVING TUBULAR FABRICS.

SPECIFICATION forming part of Letters Patent No. 283,127, dated August 14, 1883.

Application filed November 13, 1882. (No model.)

To all whom it may concern:

Be it known that I, LOWELL C. MASON, of the city and county of Providence, and State of Rhode Island, have invented a new and useful Improvement in Temples for Looms for Weaving Tubular Fabrics; and I hereby declare that the following is a full, clear, and exact description of the same, reference being had to the accompanying drawings, forming part of this specification.

This invention relates to looms for weaving tubular fabrics—such as are adapted to be cut up into endless belts—in which the weft or filling is laid in the direction of the length of the belt and the warp is laid across the belt, the weft being laid continuously from end to end of the belt thus formed; and the invention consists in the construction of devices herein-after pointed out and claimed.

Figure 1 is a sectional view of the lay and breast-beam of a loom, showing a tubular fabric in process of formation. Fig. 2 is a sectional plan of Fig. 1. Fig. 3 is a partial view of the clamp. Fig. 4 is a perspective view of the stretcher.

In weaving tubular fabrics of two or more plies—such as are intended to be cut up into endless belts—the weft must be laid with sufficient tension to secure an even strain on all the weft-threads in the different plies. This and the strain on the woven fabric required to maintain the proper tension on so large a number of warp-threads draws the fabric together on the breast-beam and narrows the same. This narrowing causes such a strain on the lay that great power is required to beat up the weft, and even with great power, in weaving an apron of the ordinary length, the lay cannot completely beat up the weft, as the latter cannot be forced into the many compacted warp-threads. Consequently fewer picks must be made than is desirable in such a fabric. The wear on the lay, as also on the warp, is objectionable independent of the loss of power. The fabric itself, when thus produced, is imperfect, and a straight endless belt cannot be so woven, as by the contraction the weft-threads are all bowed in one direction, and the belt or apron is not straight and will not run true.

The object of the invention is to relieve the lay of all the extra strain, and thus save power, relieve the warp from the wear of the lay, and thus maintain its original strength, hold the warp-threads in their proper position, and lay the weft perfectly straight, so as to produce a perfect belt or apron and enable the weaver to put more weft-threads to the inch than was heretofore possible.

In the drawings, A is the lay; B, the breast-beam; C, the warp-threads; D, the tubular fabric intended to form endless belts, as before described, woven of any desired width. E is a rectangular stretcher, usually a board. F is a clamp consisting of two strips secured together at the ends by screws and nuts g g'. f f are rounded projections used in light fabric belts. These projections serve to compress the fabric at a little distance from the edges and hold the main part of the fabric in a flat and extended position, which enables it to be drawn more easily from the stretcher. The clamp F is placed in front of the breast-beam B, and may be secured to the breast-beam. The stretcher E—usually a board of such length as will fit the interior of the tubular fabric and of such width that when resting against the clamp it will come nearly to the reed of the lay as it beats up the weft—is inserted into the fabric so as to maintain the width thereof, and thereby maintain the warp-threads in their proper relation to the lay, which will now fairly beat up each weft-thread as laid. As the stretcher rests against the clamp, or as the clamp compresses the fabric so that the stretcher cannot pass along with the fabric, the stretcher is retained always in its proper position.

The clamp F, composed of the two strips secured together at the ends by the screws g and nuts g', forms a simple, cheap, and effective device for holding the stretcher in its proper place with relation to the warp. The clamp can be quickly removed and replaced when a change in the length of belt is desirable.

I am aware that stretchers have been inserted between the warp-threads of a loom substantially as in my device. Various mechanisms—usually rollers—have been used to retain said stretcher in its proper relation to the

warp; but, so far as I know, no such device as the clamp F has been used for the purpose.

Having thus described my invention, I claim as new and desire to secure by Letters Patent—

5 The combination, with the lay and the breast-beam, of the stretcher and the clamp F, composed of parallel bars secured together at their ends by screws *g* and nuts *g'*, and provided

with the projections *f*, all substantially as described.

In witness whereof I have hereunto set my hand.

LOWELL C. MASON.
